ELECTRICAL RESISTANCE DEVICE

Louis W. Thompson, Schenectady, N. Y., assignor
to General Electric Company, a corporation of
New York

Application February 25, 1932, Serial No. 595,070

9 Claims. (Cl. 201—55)

My invention relates to electrical resistance devices, and more particularly to improvements in electrical resistance devices of the type employing an electrical conducting fluid.

5 My invention is particularly adapted for use in automatic regulators employing a variable resistance device, although it may also be employed as a manually controlled variable resistance device. In automatic regulators employing a variable resistance device in which a main control device is arranged to respond to variations in a condition to be regulated, it is usually desirable to have a variable resistance device which is characterized by ruggedness, long life, freedom from 10 contact arcing and deterioration, ease of movement from one extreme position to the other, and small amount of movement between extreme positions corresponding respectively to the maximum and minimum resistance.

15 In accordance with my invention, I provide an improved resistance device which is characterized by the above features and which, in addition, includes additional improved features which will be described more fully hereinafter.

20 It is an object of my invention to provide a new and improved electrical resistance device.

25 It is another object of my invention to provide an electrical resistance device which is characterized by long life, minimum mechanical resistance to change of electrical resistance, and a minimum required mechanical movement for a maximum change in electrical resistance.

My invention will be better understood from the following description taken in connection 30 with the accompanying drawing, and its scope will be pointed out in the appended claims.

In the drawing, Fig. 1 is a front elevation, partly in section, of an automatic voltage regulator employing my invention; Fig. 2 is an end elevation 35 of the regulator shown in Fig. 1, as viewed from the left-hand end of Fig. 1; Fig. 3 is an enlarged detail section of my resistance regulator taken on line 3—3 of Fig. 1; Fig. 4 is a longitudinal sectional view of my resistance regulator taken 40 when the resistance element thereof is in a vertical position, and Fig. 5 is a sectional view of Fig. 4 taken on the line 5—5 of Fig. 4.

Referring now to the drawing, wherein the same reference characters denote the same elements throughout the various figures, and referring particularly to Figs. 1 and 2, I show a panel board 1, of any suitable material, on which to mount the regulator. Mounted on panel 1 is a container, or envelope 2, which is preferably 45 made of an electrical insulating material, suit-

able materials being such vitreous compositions as glass, pyrex, porcelain, etc. Container 2 is pivotally mounted on panel board 1 in any suitable manner and as shown, it is mounted in a frame 3, by means of straps 4, the frame 3 carrying knife-edge projections 5, which cooperate with suitably notched brackets 6, fastened to panel board 1. Container 2 may take a variety of shapes so long as the lowermost parts of its cross section, taken perpendicular to its axis of rotation, are internally substantially circular in shape. The simplest and perhaps the best shape of such a container is an elongated cylinder, as illustrated.

50 Mounted in container 2 are a quantity of an electrically conducting fluid 7 and a solid electrical conductor 8. These conductors are so arranged that when the container 2 is in one position the solid conductor will be in engagement with the fluid conductor throughout substantially 55 the entire length of the solid conductor, while when the container is rotated to another position, the solid conductor will engage the fluid conductor at substantially only a few points on the solid conductor. The fluid and solid 60 conductors may both be composed of electrical resistance material or either one alone may be composed of relatively high resistance material while the other is of relatively low resistance 65 material. I have found, however, that best results are obtained when the fluid conductor is of relatively low electrical resistance as compared 70 with the electrical resistance of the solid conductor. Thus, in a preferred arrangement of my invention, the fluid conductor 7 is liquid mercury, while the solid conductor 8 may be any well known relatively high resistance material.

75 Resistance conductor 8 may be of almost any desired type or shape, but I have found that good results are obtained when it is in the form of a 80 resistance wire which is wound on a suitable supporting means which I have illustrated as an insulating strip 9. Resistance wire 8 and strip 9 may together be taken as a solid resistance and this combination is so mounted in container 2 85 that its contact boundary is in parallel relation with the longitudinal axis of the container. As shown, the resistance element is so mounted that 90 its longitudinal axis makes a relatively small angle with the axis of rotation of the container. 95 A convenient way of mounting the combination of resistance wire 8 and supporting strip 9, is by means of metallic plate members 10 which are 100 of a circular shape and of such a size as to fit snugly within the container 2. As shown clearly 105

110

in Fig. 4, the longitudinal axis of the solid resistance element, comprising the wire 8 wound on the support 9, makes a small angle with the axis of rotation of the container. It is by means of this angle that rotation of the container will cause varying degrees of submergence, or progressively changing points of contact, of the solid resistance material in or with the liquid conducting material. As shown in Figs. 1, 2 and 3, the container 2 is in such a position that the resistance wire 8 is just making contact with the mercury 7 at the left-hand end of the resistance. If now the container 2 is rotated in a clockwise direction as viewed in Figs. 2 and 3, the direction of motion of the contact boundary of resistance 8 will be substantially at right angles to its longitudinal axis and the point of contact between resistance 8 and the surface of the mercury will move toward the right thereby causing successive engagement of the turns of the resistance wire with the mercury.

The left-hand end of resistance wire 8 is electrically connected at 11 to the metal supporting plate 10 so that this end of the resistance wire is in electrical contact with the mercury 7. The right-hand end of the resistance wire 8 is connected to a terminal 12 which is insulated from the right-hand supporting member 10. Another terminal 13 is electrically connected to the supporting means 10. Lead-in wires 14 connect respectively to the terminals 12 and 13 and these lead-in wires 14 are sealed into the walls of the container in a manner similar to that in which the lead-in wires to an ordinary incandescent electric light bulb are sealed in.

With these connections and with the resistance regulator in the position shown in Figs. 1, 2 and 3, an electrical circuit through the regulator will begin, for example, at terminal 12, traverse substantially all of the resistance wire 8 and return through the mercury to the terminal 13. As the container 2 is rotated in a clockwise direction, as viewed in Figs. 2 and 3, the point of contact of the resistance and the mercury is moved to the right, thereby short circuiting successive turns of the resistance 8 and reducing simultaneously the length of the conducting path through both the resistance wire 8 and the conducting liquid 7.

In assembling the regulator, the container 2 will be open at its right-hand end and the strip 9 with its attached supports 10 will be slid into the container, electrical connections will then be completed between the lead-in wires 14 and the terminals 12 and 13 respectively, and then the container will be sealed at points 15.

In order to prevent oxidation and deterioration of the resistance wire 8 and also to prevent arcing between the resistance wire and the mercury, the container 2 may be evacuated or it may be filled with an atmosphere of oxidation preventing gas. This gas may actually be a reducing gas such as hydrogen or it may be a relatively inert gas such as argon, helium or nitrogen.

I have found that with the above described arrangement relatively sudden changes in the angular position of the container 2, which result in varying the degree of engagement of the resistance wire on strip 9 with the liquid in the container, cause traveling ripples to move along the surface of the liquid. These traveling ripples cause undesirable and uncontrollable resistance changes. By providing one or more spaced baffles 16 which extend into the liquid conductor, these ripples are effectively broken up and a dis-

tinct improvement in operation results. These baffles may be supported in any suitable way and as shown I provide wires, or rods, 17 for this purpose. These wires are fastened to the end supporting plates 10.

With the resistance device described above, it will be seen that in no position can the resistance of the regulator exceed the combined resistances of the resistance wire 8 and the return circuit through the liquid. This is because even if the resistance wire 8 is entirely out of contact with the mercury, the return circuit will always be made through the left-hand end plate 10 to the mercury. This is a distinct advantage as it prevents accidentally open circuiting a regulating circuit including the regulating resistance.

It will also be noted that as the container 2 is rotated from its position corresponding to maximum resistance to its position corresponding to minimum resistance of the regulator, the length of the electrical conducting paths through the solid and the liquid conductors vary simultaneously and similarly, that is to say, their maximum and minimum lengths occur together. While this is not of much advantage in cases where the fluid conductor is mercury, because of the relatively low resistance of this liquid, it is of considerable advantage in cases where the electrical resistance of the solid and fluid conductors are substantially equal.

Another advantageous result which I obtain is that the fluid, or liquid, conductor does not have to be moved in changing the resistance of the regulator and consequently the inertia forces produced when the regulator goes from one position to the other may be made relatively low because in cases when the liquid conductor is mercury, the remaining elements will be relatively light in comparison with the mercury.

It will also be seen that my resistance regulator will be balanced in any position so that it will require but a relatively small and uniform force to change it from any one position to another.

As shown in Fig. 1, I have illustrated an application of my invention to an automatic electric voltage regulator. In this figure a solenoid magnet 18 is connected across a circuit 19 whose voltage is to be regulated. The core 18a of solenoid magnet 18 is mechanically connected to the frame 3 for operating my resistance device. A suitable rheostat 20 is connected in the energizing circuit of solenoid 18 for adjusting the voltage calibration of this solenoid. For energizing circuit 19 I have illustrated a direct current generator 21 having a shunt field winding 22 whose circuit is connected to the terminals 14 of my resistance device. A conventional shunt field rheostat 23 is also provided in the shunt field winding circuit of the generator. A restraining spring 24, for opposing the pull of solenoid 18, is connected to the frame 3.

The solenoid 18 is made extra large and powerful so that it will develop operating forces on changes of voltage of circuit 19 which are sufficiently large to readily and quickly rotate my resistance device. The core 18a of the solenoid is so arranged that as it is pulled up into the magnet from its lowermost position it enters a stronger and stronger magnetic field, so that with a constant voltage applied to the terminals of the operating magnet the pull on the solenoid core increases as the core moves up into the magnet. If flat regulation is desired spring 24 is

- so constructed that its change in pull, as it is stretched due to the rotation of the resistance device, exactly equals the change in pull of the solenoid magnet resulting from its change of position. This is because with such an arrangement of solenoid and spring the pulls of the two devices will exactly balance each other at any position of the resistance device, so long as constant voltage is applied to the operating magnet. 5 80
- If a weaker spring is used, an over-compounding effect may be obtained which is useful in cases where it is desirable to compensate for line drop. If a stronger spring is used, an under-compounding effect will be obtained and this effect is useful for producing stable operation in cases where a plurality of regulated generators are connected in parallel. 10 85

- As shown in Fig. 1, the core 18a is in its uppermost position and the resistance device is in its maximum resistance position. Assume, however, that these devices are in substantially their middle positions and that the voltage on circuit 19 is normal. If now circuit conditions should change, for example, if the load on circuit 19 should increase, the voltage of circuit 19 would decrease thereby decreasing the pull of the solenoid 18, and allowing the spring to overcome the pull of the solenoid, thereby rotating the resistance device and decreasing its resistance. This increases the current through the field winding 22, thereby increasing the voltage of generator 1 and increasing the voltage of circuit 19. As soon as the voltage of circuit 19 returns to normal, the regulator will come to rest in its balanced position because in this new position the pull of the spring and the pull of the solenoid will balance each other. Similarly, if the voltage of circuit 19 increases, the pull of solenoid 18 increases, thereby rotating the resistance device in the opposite direction and increasing the value of the resistance of the resistance device, thereby decreasing the voltage of the generator 21. When the voltage returns to normal the regulator will balance in its new position.
- In order to prevent hunting of the regulator I provide a suitable dashpot mechanism 25, which is connected through a spring 26 to frame 3. Introduction of spring 26 is to permit rapid, relatively small changes in resistance of the regulator, thus increasing the speed of operation of the regulator.
- While I have shown and described a particular embodiment of my invention, it will be obvious to those skilled in the art that changes and modifications may be made without departing from my invention, and I therefore aim in the appended claims to cover all such changes and modifications as fall within the true spirit and scope of my invention.
- What I claim as new and desire to secure by Letters Patent in the United States is:
1. A variable resistance device comprising a horizontal tubular container having a longitudinal axis of rotation, an electrical conducting fluid partially filling said container to a substantially constant level and arranged for relative movement with said container, and an electrical resistance within said container in fixed relation therewith and having a longitudinal contact boundary for engagement with said fluid, said contact boundary making an acute angle with the longitudinal axis of said container.
  2. A variable resistance device comprising a container, an electrical conducting liquid partially filling said container and arranged for relative movement therewith, and an electrical resistance within said container in fixed relation therewith and having a longitudinal contact boundary substantially co-extensive with one of the dimensions of the surface of said liquid and arranged so that points of contact with said liquid change progressively along said boundary in accordance with the relative movement between said fluid and container.
  3. In combination, a substantially horizontal cylindrical container, a relatively low resistance electrical conducting liquid partially filling said container, means for rotating said container about its longitudinal axis, a relatively high resistance electrical conducting element mounted in said container in such a manner that said rotation causes varying degrees of submergence of said element in said liquid, said element having a contact boundary making a small angle with the surface of said liquid.
  4. In combination, a liquid electrical conductor, a solid electrical conductor mounted for variable engagement with said liquid conductor, and a baffle normally associated with the surface of said liquid conductor for breaking up traveling ripples on the surface of said liquid conductor.
  5. In combination, a liquid electrical conductor, a solid electrical resistance element arranged variably to engage the surface of said liquid along the length of said conductor at an effective angle with respect to the surface of said liquid which is small, and spaced baffles associated with the surface of said liquid for breaking up traveling ripples on the surface of said liquid.
  6. In combination, an elongated glass tube, supporting means for maintaining the longitudinal axis of said tube substantially horizontal and for permitting rotation of said tube about said axis, a strip of insulating material mounted in said tube in such a manner that its longitudinal axis makes a relatively small angle with the axis of said tube, an electrical resistance wire wound on said strip, a sufficient quantity of liquid mercury in said tube to cause engagement between said mercury and substantially all of the turns of said resistance wire when said strip is vertical, baffles placed at intervals in said tube to break up longitudinally traveling ripples on the surface of said mercury, and an atmosphere of reducing gas in said tube.
  7. In combination, a straight elongated glass tube having its longitudinal axis substantially horizontal, supporting means for permitting rotation of said tube about its longitudinal axis, a straight relatively thin elongated rectangular strip of insulating material rigidly mounted in said tube with its longitudinal axis making a relatively small angle with the longitudinal axis of said tube, a resistance wire wound around said strip substantially perpendicularly to its longitudinal axis, a sufficient quantity of liquid mercury in said tube to just permit engagement between said mercury and a portion of substantially each of the turns of said resistance wire when said strip is in a substantially vertical position, baffle plates mounted at intervals in said tube in engagement with the surface of said mercury, and an atmosphere of oxidation preventing gas in said tube.
  8. In combination, a container mounted for rotation about a horizontal axis and having the inside bottom surface thereof in the shape of a cylinder whose axis corresponds with the axis of said container, a resistance element having the substantial equivalent of a straight line contact

boundary mounted in said container with a small angle between said boundary and said axis, and a quantity of conducting liquid in said container for engagement with said contact boundary.

5 9. In combination, a tubular container mounted horizontally for rotation about its longitudinal axis, a strip of insulating material mounted in

said container, said strip having one edge which is a straight line making a small angle with said axis, a resistance wire wound around said strip, and a quantity of conducting liquid in said container for engagement with said resistance wire. 80
